Marion Elwin

UNITED STATES PATENT OFFICE.

CURT SCHLEIMER, OF BROOKLYN, NEW YORK.

BELT BUCKLE.

Application filed January 19, 1926. Serial No. 82,182.

This invention relates to attachments adapted for use with an ordinary belt and has as its main object, the provision of a device to keep underwear from falling.

5 A feature of the device is in the provision of an article that, while holding the belt in place, at the same time is applicable to retain a watch chain or knife hanging pendant from it.

10 A further feature is in the provision of a device whereby an undergarment is kept in place and prevented from slipping down.

A still further object of the appliance is to provide a device, whereby a garment may 15 be worn higher or lower without disturbing the position of the belt that is attached thereto.

These and other objects are accomplished by the novel construction, arrangement and 20 combination of parts hereinafter described and illustrated in the accompanying drawing, forming an essential part of this disclosure, and in which:—

Figure 1 is a partial sectional, front elevational view of a conventional pair of pants showing the application of the invention thereto.

Figure 2 is a sectional view taken on line 25 2—2 of Figure 1 and showing how the device is attached to a garment having a belt therein.

Figure 3 is a perspective view of the invention showing the details thereof.

Referring more in detail to the drawing, 35 the numeral 10 generally designates a pair of pants. Sewed thereto at convenient positions, are several vertical loops 11 made of the same material as the garment 10 and through which passes an ordinary belt 12 having a buckle 13. An undergarment 14 is 40 fitted with a plurality of spaced horizontal loops 15 to receive and hold the device in position.

The device consists of a substantially rigid, 45 open, rectangular body 16 made of leather or other like material. Sewed to the front of the body 16 is a pair of snap fas-

tener elements 17 and 17^a, lower and upper respectively, either of which may be engaged with a mating element 19 secured at 50 the end of a flap 18 sewed to the back of the body 16. Passing through the body may be a ring 20 or otherwise shaped piece of metal on which may be carried, a knife, 55 charm, etc.

In operation, the belt is passed through the body 16 of the device and loops 11 of the pants. The flap 18 sewed to the back of the body 16 is then passed through the loops 15 of the undergarment and element 19 is made 60 to engage with either of the elements 17 or 17^a, depending upon the position that the pants are desired to be in. When these elements are engaged, the combination forms a snap fastener. If the garment is to 65 be worn high, the element 17 is used; if low, the element 17^a is used.

Thus it may be seen that a pair of pants may be raised or lowered as desired without having to manipulate the belt, but by merely 70 changing the position of the snap fastener element 19, to engage with the higher or lower, as the case may be, and this undergarment prevented from slipping down 75 within the trousers.

Having thus described my invention, what I claim as new and desire to secure by Letters Patent, is:—

1. A belt attachment comprising a rigid rectangular open looped body, a pair of snap fastener elements thereon, and means by which said body is engageable with an undergarment.

2. A belt attachment comprising a rigid rectangular open looped body, a pair of snap fastener elements mounted on said body, a flap attached to said body and a third snap fastener element mounted on said flap engageable with either of the first named elements.

In witness whereof I have affixed my signature.

CURT SCHLEIMER.
